UNITED STATES PATENT OFFICE.

FRANK H. FLEEGE, OF ST. LOUIS, MISSOURI, ASSIGNOR TO ROBERT J. LEACOCK,
TRUSTEE, OF ST. LOUIS, MISSOURI.

CENTRIFUGAL SEPARATOR.

961,488.

Specification of Letters Patent. Patented June 14, 1910.

Application filed February 19, 1909. Serial No. 478,767.

To all whom it may concern:

Be it known that I, FRANK H. FLEEGE, a citizen of the United States, residing at St. Louis, Missouri, have invented a certain new and useful Improvement in Centrifugal Separators, of which the following is a full, clear, and exact description, such as will enable others skilled in the art to which it appertains to make and use the same.

10 This invention relates to centrifugal separators, and particularly to the type shown in my prior United States Patent No. 792,577, dated June 13, 1905.

One object of my present invention is to provide a separator of the type referred to having a separating cone arranged at the upper end of the bowl and constructed in such a manner that it can be removed quickly and thoroughly cleaned.

20 Another object is to provide a separator of the character described in which the cone and also the liner that is arranged inside of the bowl are subjected to yielding pressure which retains them in operative position.

Another object is to provide a separator in which the support that carries the bowl is constructed in such a manner that it can be adjusted so as to make the bowl perfectly 30 level.

Another object is to provide a centrifugal separator having a bowl for receiving the solution that is to be separated, and one or more chambers surrounding said bowl and 35 communicating with the interior thereof for receiving and collecting the constituents of said solution that are of comparatively greater specific gravity. And still another object is to provide a separator in which the 40 arms that are located inside of the bowl are arranged in a novel manner.

Figure 1 of the drawings is an elevational view, partly in vertical section, of a separator embodying the various features of my 45 invention; Fig. 2 is a horizontal sectional view of the bowl, taken on approximately the line 2—2 of Fig. 1; Fig. 3 is an elevational view, partly in vertical section, of a modified form of my invention; Fig. 4 is a 50 horizontal sectional view of the bowl shown in Fig. 3, taken on approximately the line 4—4 of said figure; Figs. 5, 6 and 7 are vertical sectional views of slightly modified

forms of bowls; and Figs. 8, 9 and 10 are horizontal sectional views of the bowls 55 shown in Figs. 5, 6 and 7, respectively.

Referring to the drawings which illustrate the preferred form of my invention, 1 designates a stationary base on which a support or standard 2 is adjustably mounted, as hereinafter described, said standard being provided with an arm or extension 3 that carries a vertically disposed shaft 4 which is adapted to be rotated by some suitable means.

65 The bowl A of the separator is connected to the shaft 4 so that it will rotate with same, and said bowl is provided with a removable top or cover B that has a screw-threaded flange 5 which is screwed onto the 70 upper end of said bowl. This cover B has a conical-shaped portion that merges into a tubular-shaped portion 6 which is provided on its interior with a beveled seat that is adapted to be engaged by a beveled collar 7 75 on the tubular-shaped portion 8 of a separating cone C that is arranged inside of the bowl A, as shown in Fig. 1. The liner that is arranged inside of the bowl consists of a hollow shaft D provided adjacent its 80 upper end with a beveled collar 9 that fits in a beveled seat on the interior of the tubular-shaped portion 8 of the cone C, the upper end of said shaft projecting into a receptacle 10 that receives the solution which is to be separated. Said shaft D is provided with a number of laterally projecting arms 11 that terminate adjacent the side of the bowl, and in the construction shown in Figs. 1 and 2, said arms 11 are screwed directly into the shaft D.

85 The beveled collars on the liner shaft D and on the cone C are held in engagement with the tapered seats which they cooperate with by yielding pressure so as to form tight joints between said parts. In the construction herein shown the liner shaft D is provided at its lower end with a number of devices 12 formed of spring material that bear upon the bottom of the bowl A and thus 100 force the shaft D upwardly so as to hold the tapered collar 9 thereon in intimate engagement with its cooperating seat on the interior of the tubular-shaped portion 8 of the cone C. The upward pressure which the 105 liner shaft is thus subjected to will, of course,

tend to move the cone C upwardly and thus hold the tapered collar 7 on said cone in intimate engagement with its coöperating seat on the interior of the tubular-shaped portion 6 of the top or cover B of the bowl. The bottom of the bowl is provided with suitable grooves or shoulders, for receiving the lower ends of the yielding devices or extensions 12 on the lower end of the liner shaft so as to cause said shaft to rotate with the bowl.

The light constituents of the solution being separated pass upwardly inside of the tubular portion 8 of the cone C and then escape through ports 13 in said tubular-shaped portion into a pan or receptacle 14, the heavier constituents of the solution passing upwardly between the separating cone C and the cover B of the bowl and escaping through ports 15 in the tubular-shaped portion 6 of said cover into a pan or receptacle 16. The receptacles 10, 14, and 16 are superimposed one upon the other, and the standard 2 is provided with a bracket 17 on which the receptacle 16 rests, as shown in Fig. 1, the receiving receptacle 10 being provided with a float 18 that controls the flow of the solution from the supply pipe 19.

When it is desired to clean the parts of the separator, the receptacles 10, 14 and 16 are removed and the top or cover B of the bowl is then unscrewed so as to enable the liner and cone to be removed. In view of the fact that the coöperating surfaces or contacting faces between the cover B and the cone, and between the cone and the liner shaft, are perfectly smooth, the parts can be removed quicker and can be cleaned more thoroughly than if said parts were connected together by screw threads as in the separators now in general use.

As it is necessary to have the bowl perfectly level I have constructed the standard 2 in such a manner that it can be adjusted 45 relatively to the stationary base 1. In the form of my invention shown in Fig. 1, the base 1 is provided with an approximately ball-shaped projection 20 that fits in a socket on the standard 2, said standard consisting of two or more sections that are held 50 together by bolts 21 which cause the standard to firmly clamp the ball-shaped projection 20 on the base and thus lock the standard in position. In the form of my invention 55 illustrated in Fig. 3 the base 1 is provided with a concaved seat and the standard 2 is provided with a convexed lower end that fits in said seat, the standard being clamped to the base by means of a bolt 21. By constructing the standard in this manner it is 60 a very simple matter to adjust it so as to make the bowl perfectly level.

One feature of my present invention which I believe is broadly new in centrifugal separation is providing the bowl with one or

more chambers for receiving and collecting the constituents of comparatively greater specific gravity. In the form of my invention illustrated in Fig. 1, the bowl A is provided with an annular chamber E that surrounds the lower portion of the bowl, the wall of the bowl being provided with a plurality of vertically disposed slots 22 that permit the heavier constituents of the solution to enter said chamber when the bowl is rotated. When the separator is being used for separating cream from milk, the bacterium in the milk, which is of greater specific gravity than the milk, will be thrown by centrifugal force through the slots 22 in the bowl and lodge in the chamber E, and the milk and cream will be forced upwardly into the receptacles 16 and 14, respectively, as previously described. I prefer to form the slots 22 tapered or approximately, wedge-shaped in cross section, as shown in Fig. 2, so that each slot will have a comparatively wide entrance and a narrow outlet which overcomes any tendency of the particles to escape from the slots back into the bowl 90 after they have once entered the slots.

If desired, the bowl can have a plurality of receiving chambers E and F', as shown in Figs. 7 and 10, so as to more finely grade the solution or effect a more thorough separation thereof, the heaviest constituents, of course, collecting in the chamber that is located farthest from the bowl. In other respects the bowl shown in Figs. 7 and 10 is similar to that shown in Fig. 1, it being provided with a hollow shaft D having laterally projecting arms 11. While I have herein shown this feature of my invention embodied in a cream separator I wish it to be understood that this feature could be embodied in any kind of a centrifugal separator that is used for separating the constituents of any suspended solution one from another. I have herein shown the chamber E formed by an approximately cup-shaped member 23 that forms the bottom of the bowl A, the sides of the bowl being formed by an open-ended cylinder that projects into the member 23 and rests on the bottom thereof. Said cylinder is of less diameter than the member 23 so that a chamber E will be formed between said parts. The upper end of the member 23 is screwed into a flange 24 on the exterior of said cylinder, as shown clearly in Fig. 1, so as to enable said parts to be separated when it is desired to remove the substance that has collected in the chamber E.

Instead of providing the liner shaft D with laterally projecting arms 11, as shown in Figs. 1 and 2, the bowl A can be provided on its interior with arms 11 that project inwardly toward the shaft D, as shown in Figs. 3 and 4. Figs. 5 and 8 show still another form of bowl in which vertically dis-

posed arms, 11^a project upwardly from the bottom of the bowl, said arms being arranged in rows that extend radially from the longitudinal center of the bowl, as shown in Fig. 8. In the bowl shown in Fig. 5 the solution is introduced into the lower end of the bowl through an opening 25 in the bottom thereof instead of being introduced through a pipe or hollow shaft that projects 5 through the cover of the bowl. The bowl shown in Figs. 6 and 9 is also provided in its bottom with an opening 25 through which the solution is introduced and instead of having the arms 11 connected directly to the 10 bowl said arms are connected to a sleeve 26 which is slipped inside of the bowl, the arms projecting inwardly from said sleeve toward the longitudinal axis of the bowl.

Having thus described my invention, what 20 I claim as new and desire to secure by Letters Patent is:

1. In a separator, a rotatable bowl for holding a solution, the upper portion of said bowl being imperforate and the lower portion 25 of the bowl being provided with slots, and a closed chamber communicating with said openings for receiving and retaining the constituents of said solution that are of the greatest specific gravity and which are 30 thrown through said openings by centrifugal force.

2. In a separator, a bowl for holding a solution, a plurality of annular chambers arranged in approximately the same horizontal plane, one within the other, and surrounding said bowl, and means for permitting the constituents of said solution in said bowl to be thrown by centrifugal force from 35 said bowl and collected in said chambers.

3. In a separator, a rotatable bowl for holding a solution, a chamber surrounding said bowl, and slots in the sides of said bowl above the bottom thereof for permitting the constituents of said solution to be thrown by 45 centrifugal force into said chamber and collect therein, the upper portion of the bowl being imperforate.

4. In a separator, a rotatable bowl for holding a solution, the side walls of said bowl being provided with approximately 50 vertically disposed slots that terminate adjacent the bottom of the bowl, and a continuous annular chamber surrounding said bowl for collecting and retaining the constituents of said solution that are thrown through said slots by centrifugal force.

5. In a centrifugal separator, a bowl for holding a suspended solution, the side walls of said bowl being provided with vertically 55 disposed slots which are of greatest dimensions on the inner side of the bowl, and a hollow member surrounding said bowl to form a chamber which receives and retains the solution that is thrown through said 65 slots by centrifugal force.

6. In a separator, a rotatable bowl, means for introducing a solution into said bowl, substantially vertical slots in the sides of said bowl, and a hollow member detachably connected to said bowl and forming a chamber that communicates with said slots for collecting and retaining the constituents of said solution that are thrown through said slots by centrifugal force. 70

7. In a separator, an approximately cup-shaped member, a cylinder of less diameter than said member and arranged inside of same, a laterally projecting flange on the outer surface of said cylinder provided with a depending ring-shaped portion to which the upper edge of said cup-shaped member is connected by means of screw threads, and openings in said cylinder that establish communication between the interior of the cylinder and said cup-shaped member. 75

8. In a separator, a rotatable bowl, means for introducing a suspended solution into said bowl, receptacles arranged adjacent the upper end of the bowl, means for causing different constituents of the solution to enter 90 said receptacles when the bowl rotates, and a chamber arranged outside of said bowl and communicating with openings in the sides of the bowl for collecting the heavier constituents of said solution that do not enter 95 said receptacles.

9. In a separator, a rotatable bowl, means for introducing a suspended solution into said bowl, receptacles arranged adjacent the upper end of the bowl, means for causing 100 different constituents of the solution to enter said receptacles when the bowl rotates, a chamber surrounding the lower portion of the bowl, and slots formed in the side walls of the bowl above the bottom thereof so as 105 to permit the heavier constituents to be thrown outwardly by centrifugal force into said chamber.

10. In a separator, a rotatable bowl for receiving the solution that is to be separated, 110 a top or cover for said bowl, a separating member spaced away from the inner face of the cover and conforming to the shape thereof, a hollow shaft projecting into said bowl and provided with means for engaging 115 said separating member, and yielding fingers on the lower end of said shaft that bear against the bottom of the bowl and thus exert upward pressure on said shaft so as to retain said separating member in position. 120

11. In a separator, a bowl provided with a removable cover having a tapered recess on the interior thereof, a cone-shaped separating member provided with a beveled collar that fits in said recess and having its lower edge spaced away from the side of the bowl so as to permit the solution being separated to pass between said member and cover, and a spring for exerting upward 130

pressure on said separating member so as to hold the collar thereon seated in the recess in said cover.

12. In a separator, a bowl provided with 5 a removable cover having a substantially tubular-shaped portion, a cone-shaped separating member having a tubular-shaped portion that fits inside of the tubular-shaped portion on said cover, the lower edge of said 10 member being spaced away from the side of the bowl so as to permit the solution being separated to pass between said member and cover, coöperating inclined faces on said tubular-shaped portion, and a spring 15 for facing said separating member upwardly so as to hold said inclined faces in intimate engagement with each other.

13. In a separator, a rotatable receiving 20 bowl, a cover for said bowl provided with a tubular-shaped portion which is provided on its interior with a beveled seat, a separating device having a tubular-shaped portion that projects through the tubular-shaped portion on said cover, a beveled collar on 25 said separating device that engages the seat on the cover, a hollow shaft projecting through said separating device and having a portion that engages same, and yielding means for forcing said shaft upwardly so as 30 to hold the collar on said separating device in intimate engagement with the seat on said cover.

14. In a separator, a rotatable receiving 35 bowl, a liner shaft projecting into said bowl and provided with a beveled collar, a separating cone having a tubular-shaped portion that surrounds said liner shaft and engages the collar thereon, the tubular-shaped por-

tion of said cone being provided on its exterior with a beveled collar, a cover for said 40 bowl having a portion that cooperates with the collar on said separating cone, and yielding means for holding the cone in engagement with said cover and the liner shaft in engagement with the tubular-shaped portion 45 of the cone.

15. In a separator, a rotatable receiving 50 bowl, a cone-shaped cover detachably connected to said bowl and provided with a tubular-shaped portion, a separating cone 55 arranged inside of said cover and provided with a tubular-shaped portion that has a beveled collar which fits in a tapered recess on said cover, a liner shaft projecting into the bowl and having a beveled collar that fits in a tapered recess on the tubular-shaped portion of the cone, and yielding devices connected to the lower end of said liner shaft and engaging the bottom of said bowl.

16. In a separator, a rotatable bowl for 60 containing matter in suspension, and horizontally disposed arms arranged inside of said bowl and terminating near the center of the bowl.

17. In a separator, a rotatable bowl for 65 containing matter in suspension, and horizontally disposed rods connected to the interior of said bowl and projecting toward the longitudinal axis thereof.

In testimony whereof I hereunto affix my 70 signature in the presence of two witnesses, this sixteenth day of February 1909.

FRANK H. FLEEGE.
